(54) **WATER WHEEL**

(76) Inventor: **Isaac Van Gorder**

*Isaac Van Gorder of Trumbull Co. Ohio
Letters Patent.*

The schedule referred to in these Letters Patent and making part of the same, containing a description in the words of the said Isaac Van Gorder himself of his Improvement in water-wheel wheels.

It all to whom these presents shall come. Be it known that I, Isaac Van Gorder of Trumbull County and State of Ohio, have invented a new and useful improvement in the water-wheels of mills, which improvement consists in the application of water to mill wheels, formed as is herinafter described, for the purpose of creating a rapid revolution, per force of the pressure, gravitation and motion of the water applied, and that the following is a full and exact description of the said invention or improvement, as invented or improved by me. When the said wheel to be used is about ten feet, the body of the wheel may be ten feet diameter by eight inches thick, made out of a solid piece of green timber the grain of which should be parallel to the axis. This might afford about three feet long and eight inches diameter furnished with a step judgment at the top and at the upper end, with a clevis or coupling judgment to allow the wheel's shaft to be cut out to any desired length, or the shaft may be entire and of the whole length desired. on this the wheel should be hung about six inches from the lower end.

In the step judgment there should be a concave or socket about one inch deep that would fit on a convex point or end of an upright post or stake set in a bridge or piece of wood about ten or eight inches square, and long enough to be fastened at its ends to the flume or race herein after described.

The aforesaid concave point and socket should be hardened steel, the upright post, or stake may be the same material, or of iron, upon the periphery of the wheel fix at regular distances about twenty buckets, making those about two and a half inches broad each, and about eleven inches deep each, of tough rolled iron at least one quarter of an inch thick.

These buckets should be curved in their depth the radius of the curve being about eleven inches. The edges of the pieces of iron

that form the buckets, then are to be placed against and fixed in the rim or periphery of the wheel, and be also curved so as to fit close to said rim. The upper ends of the buckets should be level with the top of the wheel, and the buckets should be so placed that the water may flow or strike against their upper or concave sides. They should be secured firmly to the wheel by screws or bolts, passed through the upper and lower ends of the pieces of iron, forming said buckets, near the inner edge of said ends, the said pieces being cut wider at their ends than elsewhere to allow them to be let into saw kerfs cut into the rim of the wheel near the top and bottom thereof. When the buckets are formed thin outer edges must be turned or otherwise brought as by filing to a true circle.

The wheel having been thus made a strong wooden frame is next to be formed and caised so as to be perfectly tight, with planks two inches and a half thick on its top and sides and on its bottom with planks two inches thick crossed or lashed together four ways, which are firmly nailed or pinned to each other. Through this bottom cut a circular hole or cast sufficiently large to allow the wheel and its buckets to revolve therein freely. This cast may be lined or caised with sheet iron. But before the top of said cast is fastened or put on, a platform or guard should be made of green plank doubled or crossed and nailed or pinned together about three inches thick which platform should rest on the upper surface of the bottom of said cast in the centre of this aff. This platform a hole must be cut of circular form of equal diameter in the lower surface as to the diameter of the hole in the cast but of greater diameter by two inches on the upper surface in this hole saw kerfs should be cut into which pieces of cold iron of about an eighth of an inch thick must be let into to form shutes or guides in number corresponding to the buckets of the wheel, but they are to be placed or inclined in an opposite direction to the inclinations of the buckets and so as to form an angle of about 30 degrees below the horizon.

tal time. The inner edges of the pieces of iron forming the staves are to be let into saw kerfs cut into a cylindrical centre of green plank doubled and pinned together three inches thick, the diameter of which should be precisely the same as that of the body of the wheel, the said centre being connected with the platform by said thicknesses of iron and also by three strong iron bolts, and having a hole cut in its middle thro' which the axis, or shaft of the wheel may go thro' and thus forming a guard to the wheel. The parts hereinbefore described being constructed as aforesaid, and adjusted so that these wheel are to move in easy work without any unusual friction, the water may be conveyed by a trunk into the side or top of the case above the level of the upper surface of the platform or guard and be let out by drawing, or be shut off by closing a gate that should be placed at the top of the trunk. These revolutions which a wheel will make, if constructed as aforesaid and driven by a head of ten feet of water would exceed two hundred in a minute.

This wheel however may be made to run in other than horizontal directions, it may be placed vertically or at any desirable angle, and it as well as the case may be made of cast iron instead of wood or partly of each and it will run as well when placed near to the top of the head of water as if placed low. Provided a light trunk or case shall be continued from the bottom of the case or flame beneath the surface of the tail or waste water.

This wheel will run as well in thin or under the water as out of it and may be protected from the weather by being covered in st. under a sixteen foot head of water three hundred revolutions of this wheel may be had in a minute.

By varying the diameter of the wheel and its depth, and enlarging or contracting the rising ends of the buckets, and the breadth and depth and curvatures or angles of the buckets, the velocity of the wheel may be increased or diminished and

the water power may be applied as may be most advantageous & conformable to the objects of the persons employing this invention and its revolutions may be varied from one hundred to three hundred to three thousand per minute so as in most cases to obviate the necessity and save the expense of the gearing required to go up speed. And power may be augmented by putting two wheels, having opposite issues within the case or flume on the same axis and still more by putting additional cases or flumes with pairs of wheels thereon.

What I claim as my invention or improvement is the construction of a water wheel to run in a case or cylinder as above described protected by a platform or guard from the weight or pressure of the column of water employed and defending the axis of the wheel from the excessive friction which that weight or pressure would create at or on the pivot of said axis also the manner of applying water at the periphery of a wheel thro' shutes or guides placed in a protecting platform or guard so as to impel a wheel with a case or cylinder and flume or case per force of the perception gravitation and reaction of the water applied

Signed.
